CLAIM

The ornamental design for a spice injection-type meat tenderizer, as shown and described.

DESCRIPTION

FIG. 1 is a front elevational view of a spice injection-type meat tenderizer showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof; and

FIG. 7 is a perspective view thereof; and,

FIG. 8 is a reference view thereof.

(Continued)

The broken lines showing environment and portions of the article form no part of the claimed design.

1 Claim, 8 Drawing Sheets
